CLAIM

The ornamental design for an electrocardiography monitor, as shown and described.

DESCRIPTION

FIG. 1 is a perspective view showing an electrocardiography monitor.

FIG. 2 is a top plan view of the electrocardiography monitor.

FIG. 3 is a bottom plan view of the electrocardiography monitor.

FIG. 4 is an enlarged front elevational view of the electrocardiography monitor.

FIG. 5 is an enlarged rear elevational view of the electrocardiography monitor.

FIG. 6 is a right elevational view of the electrocardiography monitor.

FIG. 7 is a left elevational view of the electrocardiography monitor.

FIG. 8 is another perspective view thereof, in which the electrocardiography monitor is shown in an example environment, as shown in broken lines.

The broken lines in FIG. 8 represent environmental subject matter and all other broken lines in the drawing views illustrate unclaimed portions of the electrocardiography monitor. None of the broken lines form part of the claimed design.
